[57] **CLAIM**

The ornamental design for a lighted transportable compact mirror, as shown and described.

DESCRIPTION

FIG. 1 is a front elevational view of a lighted transportable compact mirror showing our new design;
FIG. 2 is a side elevational view thereof, the other side being the mirror image;
FIG. 3 is a top plan view thereof;
FIG. 4 is a bottom plan view thereof; and
FIG. 5 is a rear elevational view thereof.
